[57] **ABSTRACT**

Water-soluble dyestuffs having an affinity for fibers and being capable to dyeing in the absence of reducing agents obtained by reacting water-insoluble sulfur dyestuffs, reduction products thereof or their thiosulfuric acid derivatives with alkylenimines and substituted derivatives thereof.

5 Claims, No Drawings

WATER-SOLUBLE SULFUR DYESTUFFS

In practice, the water-insoluble sulfur dyestuffs are dissolved with sulfur alkalies, in particular with sodium sulfide, applied to cellulose containing textiles in the form of their leuco compounds from the thusly obtained dyeing liquors and the insoluble sulfur dyestuffs are then fixed onto the fiber by a subsequent oxidation process.

Dyeing with the water-soluble thiosulfuric acids of the sulfur dyestuffs is carried out similarly. This process, too, requires sulfur alkalies in order to split off the thiosulfuric acid residues with the formation of the leuco compounds having an affinity for fibers and, thus, to enable the dyestuff to go onto the fibers.

The above dyeing methods necessarily involve the formation of rather large amounts of highly sulfur-containing waste water which are difficult to purify. Consequently, for some time, efforts have been made to develop methods which would allow fixing sulfur dyestuffs onto cellulosic textiles without the addition of reducing agents.

British Pat. No. 787,878 describes a method according to which fixation may be achieved by padding cotton and regenerated cellulose with the solutions of the water-soluble thiosulfuric acid derivatives of sulfur dyestuffs being free from reducing agents and subsequently heating the padded material to an elevated temperature. This method is, however, inferior to the above methods comprising the addition of sulfur alkalies, with regard to the fixation of the dyestuffs and the fastness properties of the dyeings obtained therewith. Furthermore, U.S. Pat. No. 3,294,476 describes a method that consists of padding the textiles with dye liquors containing, in addition to the water-soluble thiosulfuric acids of the sulfur dyestuffs or their salts, bi- or poly-functional substances that yield together with the sulfur dyestuffs stable reaction products and may, moreover, contain acid or alkaline catalysts, submitting, if required, the thusly treated textiles, after drying, to a moist or dry-heat treatment and finishing them as usual. One drawback consists, however, in that the thiosulfuric acids of the sulfur dyestuffs have no affinity for cellulose fibers when applied without the addition of reducing agents and, consequently, cannot be dyed according to the exhaust process.

It has now been found that water-soluble sulfur dyestuffs having an affinity for fibers and being capable of dyeing in the absence of reducing agents are obtained by reacting, preferably in the presence of catalysts, water-insoluble sulfur dyestuffs, reduction products thereof or a thiosulfuric acid derivative thereof with alkylenimines that may be substituted. Ethylenimine is particularly preferred.

Apart from ethylenimine, particularly suited for the process of the present invention are, for instance, 1,2-propylenimine, N-acetylenimine, β -ethyleniminopropionamide, N-methylethylenimine, 2,2-dimethylethylenimine, 2,3-dimethylethylenimine, methyl- β -ethyleniminepropionate and 2-ethylethylenimine. Catalysts having a favorable effect on the reaction are, for instance, ethylenechloride and epichlorhydrin.

The reaction with the alkylenimines is carried out at temperatures ranging from about 15° to 120° C., preferentially about 40° to 120° C. Preferably, it is car-

ried out in an aqueous medium or in an organic solvent, preferably a lower alkanol or dimethylformamide, which may be diluted with water, whereby the initial dyestuffs are either present in the form of a suspension or may be dissolved partly or in total.

If water-insoluble sulfur dyestuffs are employed as initial dyestuffs and the reaction is terminated, i.e., a sample of the reaction products dissolves without leaving a residue in water which may be weakly acidified, unreacted alkylenimine, if any, may be polymerized by the addition of a catalyst, such as ethylenechloride or epichlorhydrin and by the introduction of CO₂ or SO₂.

In order that sulfur dyes are obtained that dissolve already in neutral water the reaction mixture is, when the reaction is terminated, adjusted to an acid pH, preferably to pH of about 4 to 5. If the mixture does not show an acid reaction at the end of the reaction period there are obtained sulfur dyes that readily dissolve in acidified, preferentially in acetylated water. Towards the end of the reaction period, a pH of about 4 to 5 can be attained advantageously by passing CO₂ or SO₂ into the reaction mixture. Consequently, during the reaction the pH value of the reaction mixture falls from the alkaline into the neutral range and finally to a pH of about 4 to 5. The CO₂ or SO₂ passed in has a catalytic effect on the exothermic reaction whereby presumably part of the alkylenimine simultaneously reacts with polymerization.

The sulfur dyestuffs obtained according to the process of the present invention are obtained in the form of more or less viscous pastes being easily soluble in water that may be weakly acidified. They have an affinity for cellulose fibers and, consequently, may be employed without the addition of reducing agents for the dyeing of cellulosic textiles according to the exhaust process. Moreover, they may be padded, for instance, onto cellulose materials, whereby the fixation of the dyestuffs may be achieved, after an intermediate drying, if required, by moist or dry-heat treatment.

Thus obtained in an easy way and without the formation of sulfur-containing waste water, are deep dyeings that distinguish themselves by good fastness properties, in particular by an excellent fastness to wet processing.

The following Examples are given for the purpose of illustrating the present invention. All temperatures are given in degrees centigrade.

EXAMPLE 1

a. 100 g. Hydrosol Fast Yellow G (Color Ind. Solubilized Sulfur Yellow 5; thiosulfuric acid from Immedial Fast Yellow GWL, the constitution of which is described in Coll. Czech. Chem. Comm. 27 (1962) 1,533-48) are suspended in 80 c.c. water. Subsequently, 48 c.c. ethylenimine are added dropwise with stirring at room temperature and the reaction vessel is put into a bath which was heated to 80°. When the temperature of the reaction mixture has reached 55°, 0.7 c.c. epichlorhydrin are added and a weak CO₂ gas stream is introduced. The temperature then rises automatically within 15 minutes to 99°. Subsequently, the introduction of CO₂ gas is stopped and the reaction mixture is stirred for another hour at 100°. Thus, there is obtained, after cooling down, a brown, viscous dye paste that is easily soluble in water.

b. 1 g. of this dye paste is dissolved in approximately 50 c.c. water of 50°-60° and filled up with cold water to give 200 c.c. The thusly prepared dyebath is adjusted with acetic acid to a pH value of 7. At 25°-30°, a cotton hank is introduced and moved in the bath. The liquor ratio is 1:20. Then the temperature of the dyebath is elevated during approximately 30 minutes to 90°-95° and the cotton hank which is moved from time to time, is dyed during 1 hour at this temperature, until the dyestuff has gone onto the material. Subsequently, the dyed hank is thoroughly rinsed and dried. Thus obtained is a deep yellow dyeing having a good fastness to wet processing.

An even better exhaustion of the dyestuff is achieved by the addition of 3 g./l. urea to the dyebath.

EXAMPLE 2

100 g. Hydrosol Fast Yellow G (see Example 1a) are pasted on with 40 c.c. water and than 60 c.c. ethylenimine are added. After the addition of 0.3 c.c. ethylenechloride, a CO₂ gas stream is introduced into the reaction mixture at 40°. The reaction that takes place is exothermic, whereby the temperature rises in the course of 18 minutes to 106°. The introduction of CO₂ gas is then cut off and stirring is continued for another 4 hours at a bath temperature of 100°.

The viscous brown dye paste being formed is easily soluble in water. Its behavior with regard to the dyeing properties is similar to that of the dye paste obtained according to Example 1.

EXAMPLE 3

100 g. Hydrosol Fast Yellow G (see Example 1a) are suspended in 80 c.c. water. After the addition of 48 c.c. ethylenimine and 0.2 c.c. aqueous hydrochloric acid 10 N, the reaction mixture is slowly heated to 90°. In the course of 2 hours a viscous brown product is obtained without an exothermic reaction occurring.

The same result is achieved by employing instead of 0.2 c.c. aqueous hydrochloric acid 10N

0.1 c.c. diethylsulfate
0.1 c.c. sulfuric acid 10N.

In all cases water-soluble, viscous products are obtained that yield on cellulosic materials without the addition of reducing agents yellow dyeings having good fastness properties.

EXAMPLE 4

100 g. Hydrosol Fast Yellow G (see Example 1a) are suspended in 80 c.c. water. After the addition of 48 c.c. ethylenimine, the reaction mixture is heated to 80° and while maintaining this temperature, SO₂ gas is introduced. In the course of this process the temperature of the reaction mixture rises during 12 minutes to 103°. After stopping the introduction of SO₂ gas, stirring is continued for another hour at a bath temperature of 100°.

The reaction product, a brown, viscous paste, is easily soluble in water; its behavior in the dyeing is similar to that of the products obtained according to the preceding Examples.

EXAMPLE 5

20 g. Immedial Fast Yellow GWL (Color Ind. Sulfur Yellow 5; sulfur dyestuff the constitution of which is described in Coll. Czech. Chem. Comm. 27, (1962) 1533-48) are suspended in 60 c.c. water. After the addition of 24 c.c. ethylenimine, the reaction mixture is heated for 6 hours under reflux. Then it is cooled down to 40° and a further 15 c.c. ethylenimine are added. Subsequently, SO₂ gas is introduced into the reaction mixture, whereby the temperature reaches 94° in the course of 14 minutes. After the decay of the exothermic reaction, the introduction of the SO₂ gas is stopped and stirring is continued for another 4 hours at a bath temperature of 100°.

Thus obtained is a brown, viscous product that easily dissolves in water.

EXAMPLE 6

100 g. Hydrosol Fast Yellow G (see Example 1a) are suspended in 80 c.c. water. After the addition of 48 c.c. ethylenimine and 0.1 c.c. epichlorhydrin, SO₂ gas is introduced at room temperature. In the course of the reaction the temperature of the reaction mixture rises within 10 minutes to 102°. After the decay of the exothermic reaction, the introduction of SO₂ gas is stopped and stirring is continued for another 4 hours at a bath temperature of 100°.

The reaction product, a brown viscous paste, is easily soluble in water.

EXAMPLE 7

A mixture of 10 g. Immedial Fast Yellow GWL (see Example 5) and 50 c.c. ethylenimine is heated under reflux for 3 hours. The brown residue remaining after distilling off the unreacted ethylenimine (38 c.c.) gives a limpid solution, when dissolved in water, which was acidified with acetic acid.

EXAMPLE 8

50 g. Immedial Fast Yellow GWL (see Example 5) are suspended in 100 c.c. water and boiled with the addition of 17 g. Na₂S (60 percent flakes) until the dyestuff is dissolved. The solution is cooled down to 50°, 50 c.c. ethylenimine and 0.1 c.c. epichlorhydrin are added and a CO₂ gas stream is passed through the reaction mixture. In the course of 10 minutes the temperature rises to 100°. After the decay of the exothermic reaction, stirring is continued for another hour at a bath temperature of 120°.

A brown, viscous product is obtained that gives a limpid solution when dissolved in diluted acetic acid.

EXAMPLE 9

50 g. Immedial Fast Yellow GWL (see Example 5) are suspended in 75 c.c. water. 17 g. Na₂S (60 percent flakes) are introduced into the aqueous suspension and heated under reflux until the dyestuff has dissolved. After cooling down to 50°, 50 c.c., 1,2-propylenimine and 0.1 c.c. epichlorhydrin are added and CO₂ gas is introduced into the reaction mixture. In the course of 10 minutes the temperature rises to 91°. After the decay of the exothermic reaction stirring is continued for another hour at a bath temperature of 120°. A brown, slightly viscous product is obtained that gives a limpid

solution, when dissolved in water, which was acidified with acetic acid.

Analogously the reaction according to the present invention can be carried out with

N-acetyl-ethylenimine
 β -ethyleniminopropionamide
 N-methylethylenimine
 2,2-dimethylethylenimine
 2,3-dimethylethylenimine
 methyl β -ethyleniminopropionate and
 2-ethylethylenimine.

EXAMPLE 10

50 g. Immedial Fast Yellow GWL (see Example 5) are suspended in 75 c.c. water. After the introduction of 17 g. Na₂S (60 percent flakes), the suspension is heated under reflux until the dyestuff has dissolved. After cooling down to 50°, 35 g. β -ethyleniminopropionamide, 10 c.c. ethylenimine and 0,1 c.c. epichlorhydrin are added. Subsequently, CO₂ gas is introduced, whereby the temperature of the reaction mixture rises in the course of 16 minutes to 84°. After the decay of the exothermic reaction, stirring is continued for another hour at a bath temperature of 120°. Thus obtained is a brown, viscous reaction product that gives a limpid solution when dissolved in diluted acetic acid.

A similar result is obtained if the reaction is carried out with a mixture of

20 c.c. ethylenimine and
 30 c.c. propylenimine.

EXAMPLE 11

a. 100 g. of a green sulfur dyestuff prepared according to the description given in Example 1 of U.S. Pat. No. 2,395,117, are suspended in 1150 c.c. water. After the addition of 70 g. Na₂S (60 percent flakes), the suspension is heated under reflux until a deep green solution is formed. After cooling down to 60°, 125 c.c. ethylenimine and 10 c.c. epichlorhydrin are added. Subsequently, CO₂ gas is introduced into the reaction mixture, whereby the temperature rises in the course of 40 minutes to 84°. After the decay of the exothermic reaction, the viscous product is stirred for another 30 minutes at a bath temperature of 110°.

Thus obtained is a viscous, deep green product that gives a limpid solution when dissolved in diluted acetic acid.

b. A cotton cheese bobbin is dyed on the dyeing machine with 5 percent of the thusly obtained dyestuff (liquor ratio 1:10). For this purpose, the dyestuff is dissolved in hot water (60°) and diluted by the addition of cold water to adjust the liquor ratio of 1:10, whereby the temperature of the liquor reaches 25°-30°. Subsequently, the dye liquor is adjusted to a pH value of 7 by the addition of acetic acid, then 5 g./l. urea are added and the dyeing is started with an alternating liquor circulation. After approximately 15 minutes, the dye liquor is heated within 30 minutes to 90°-95° and this temperature is kept for 1 hour. Subsequently, the dyed material is rinsed with cold water. In this dyeing process the dyebath is exhausted until it becomes colorless. Thus obtained is a deep green dyeing having an excellent evenness and a good fastness to wet processing.

c. A polyacrylonitrile cotton mixed fabric (50/50) is dyed in a single bath with 3 percent of the green dyestuff obtained according to the above Example 11a) and 3 percent Astrazon Orange R (Color Index 48040 "Basic Orange 27"). The dyestuffs that are separately dissolved in hot water of appr. 70°-80° are brought together and added to the dyebath that was previously admixed with 5 g./l. urea and the pH of which was adjusted to 6 with acetic acid. Dyeing is started at 30°, then the temperature is raised within one-half hour to 105° and the dyeing is continued for 1 hour at this temperature. After slow cooling down to 50°, the dyed material is thoroughly rinsed, subsequently soaped at 80°-90 and finished after a further rinsing operation. Thus obtained is a bicolor dyeing having very good fastness properties.

d. A paper pulp suspension consisting of
 60 kg cellulose fiber
 60 kg pulp of bleached pine sulphite
 60 kg pulp of bleached sulphate
 30 kg cotton linters
 having a degree of grinding of approx. 40° SR and a solid content of 7 percent by weight is admixed in a holander beater with the usual additives such as wetting agents, sizing agents and fillers and with 6 percent of a dyestuff solution consisting of 1 part by weight of the dyestuff described in para a) and 3 parts by weight of water. The dyestuff goes immediately onto the fiber and in the subsequent sheet formation on the paper machine, a colorless waste water is obtained. The thusly prepared green paper distinguishes itself by excellent fastness properties, in particular by a very good fastness to light and to bleeding out.

EXAMPLE 12

a. 50 g. Immedial Fast Brown GGL (Color Index 53327) are suspended in 100 c.c. water. After the addition of 50 g. Na₂S (60 percent flakes), the suspension is heated under reflux until a brown solution is formed. The reaction mixture is then cooled down to 60° and 100 c.c. ethylenimine and 1.0 c.c. epichlorhydrin are added. Subsequently, CO₂ gas is introduced whereby the reaction that takes place immediately is strongly exothermic. The reaction is controlled by cooling so that it ensues under weak reflux. In the course of 50 minutes the temperature of the reaction mixture rises to 102°. After the decay of the exothermic reaction, stirring is continued for another 2 hours at a bath temperature of 120°. Thus obtained is a brown, viscous product that gives a limpid solution when dissolved in water.

b. 60 g. of the thusly obtained dyestuff are dissolved in 300 c.c. distilled water and filled up with cold water to reach an amount of 1 liter. The liquor being formed has a temperature of 20°-25° and the pH value is adjusted with acetic acid to 5. With this liquor a cotton fabric is padded on the padding machine and squeezed off so as to retain 75 percent of its weight of the dye liquor. The impregnated fabric is dried and heated for 1 minute to 200°. Obtained is a brown dyeing having very good fastnesses to wet processing.

An improvement of the fixation of the dyestuff is achieved if 10-20 g./l. urea are added to the above padding liquor having a temperature of 25°-30° and a pH of 5-7.

The following sulfur dyestuffs were reacted according to the method described in Example 12.

Ex. No.	Sulfur dyestuff	Color Ind.	H ₂ O c.c.	ethylenimine c.c.	Na ₂ S g. 60%	Epi-chlorhydrin c.c.
13	Immedial Indone RR	53440	120	50	30	0.2
14	Immedial Red Brown 3B	53720	100	50	30	0.2
15	Immedial Yellow Brown G	53055	100	50	20	0.2
16	Immedial Orange Brown RR	53015	100	50	30	0.2
17	Immedial Yellow Olive 5G	53065	100	50	20	0.2
18	Immedial Fast catch 4RL	53320	250	50	25	0.2
19	Indocarbon CL	53290	100	60	25	0.1
20	Immedial New Blue FBL	53470	100	50	25	0.2
21	Immedial Direct Blue RL	53235	150	65	30	0.2
22	Hydron Blue G	53640	100	100	35	0.3
23	Immedial Black Brown AN	53000	100	50	25	0.2
24	Immedial carbon CBO	53185	100	100	30	0.2

The reaction products are viscous dye pastes which are easily soluble in water or diluted acetic acid and yield, when applied without the concurrent use of reducing agents onto cellulosic materials dyeings with good fastness properties.

EXAMPLE 25

50 g. Immedialcarbon CBO (Color Index 53185) are suspended in 80 c.c. water and, after the addition of 100 c.c. ethylenimine, heated during 3 hours under reflux. After cooling down to 60°, 0.1 c.c. ethylenechloride are added and subsequently CO₂ gas is introduced into the reaction mixture, whereby the temperature rises in the course of 12 minutes to 85°. After the decay of the exothermic reaction, stirring is continued for another hour at a bath temperature of 120°. The reaction product, a viscous, black paste, is easily soluble in water; it yields, when applied onto cellulosic textiles, black dyeings having a good fastness to wet processing.

EXAMPLE 26

50 g. Immedialcarbon CBO are suspended in 80 c.c. water and heated, after the addition of 100 c.c. ethylenimine, during 2 hours under reflux. After cooling down to 60°, SO₂ gas is introduced into the reaction mixture, whereby the temperature rises in the course of 10 minutes to 94°. After the decay of the exothermic reaction, stirring is continued for another hour at a bath temperature of 120°.

The reaction product, a viscous black paste, is easily soluble in water; its dyeing properties come up to those of the dyestuff obtained according to Example 25.

EXAMPLE 27

50 g. Immedial Indone RR extra (Color Index 53440) are suspended in 80 c.c. water and 48 c.c. ethylenimine are slowly added whereby an exothermic reaction occurs. The introduction velocity of the ethylenimine is controlled so that the reaction takes place under a weak reflux. Towards the end of the reac-

tion the temperature reaches 98°. After the decay of the exothermic reaction, stirring is continued for another hour at a bath temperature of 120°, the reaction mixture is cooled down to 60° and after the addition of 1.0 c.c. epichlorhydrin, CO₂ gas is introduced during 15 minutes. Finally, the mixture is heated again for 1 hour at a bath temperature of 120°.

The reaction product thus obtained in the form of a viscous blue paste dissolves in an acid aqueous solution having a pH value <6.8.

EXAMPLE 28

50 g. Immedial Red Brown 3B (Color Index 53720) are suspended in 80 c.c. water. After the addition of 48 c.c. ethylenimine, the suspension is heated during 3 hours under reflux, and then cooled down to 60°. 1.0 c.c. epichlorhydrin are added and CO₂ gas is introduced. In the course of this reaction the temperature reaches 102° within 8 minutes. After the decay of the exothermic reaction, stirring is continued for another hour at 120°. The reaction product thus obtained is a brown, viscous paste that easily dissolves in water and yields, when applied without the addition of reducing agents onto cellulosic material, reddish brown dyeings having good fastness properties.

The following sulfur dyestuffs were reacted according to the method described in Example 28 with ethylenimine to form water-soluble products.

30

Ex. No.	Sulfur dyestuff	Color Ind.	H ₂ O c.c.	Ethylenimine c.c.	Epi-chlorhydrin c.c.
29	Immedial Yellow Olive 5G extra	53065	80	48	1.0
30	Immedial Green BB	53571	80	100	1.0
31	Immedial Fast Cutch 4 RL	53320	80	100	1.0
32	Immedial Yellow Olive 5G	53065	80	100	1.0

39	Immedial Yellow Brown G	53055	80	48	1.0
40	Hydrosol Black B	100 g. 53186	140	10	0.1
41	Hydrosol Black B	50 g. 53186	80	48	1.0

60

EXAMPLE 42

50 g. Immedial New Blue FBL extra (Color Index 53470) are suspended in 80 c.c. water. Subsequently, 100 c.c. ethylenimine are added dropwise with cooling so that the temperature of the reaction mixture does not exceed 90°. After the decay of the exothermic reaction, stirring is continued for 45 minutes at a bath temperature of 100° and subsequently the unreacted

ethylenimine, if any, is distilled off in the vacuum. The dyestuff solution thus obtained may be indefinitely diluted with water.

Analogously, the following sulfur dyestuffs were reacted to form water-soluble dyestuffs:

Immedial Fast Brown GGL—Color Index 53327
Indocarbon CL conc.—Color Index 53290
Immedialcarbon CBO—Color Index 53185
Immedial Indone RR—Color Index 53440.

EXAMPLE 43

50 g. Hydron Blue G. (Color Index 53640) are suspended in 200 c.c. ethanol and, after the addition of 75 c.c. ethylenimine, heated during 3 hours under reflux. After cooling down, the reaction mixture is sucked off. On the filter there remain 53 g. of a finely pulverizable blue dyestuff that gives a limpid solution if dissolved in acidified water having a pH value of <6.

The deep blue filtrate additionally yields after evaporation to dryness in the vacuum 32 g. of a blue, viscous paste that gives a limpid solution when dissolved in water.

Both reaction products yield, when applied without the addition of a reducing agent, onto cellulose fibers 25 deep blue dyeings having good fastness properties.

EXAMPLE 44

50 g. Immedial Indone RR extra (Color Index 53440) are suspended in 200 c.c. methanol and, after the addition of 75 c.c. ethylenimine, heated during 3 hours under reflux. After cooling down, the reaction mixture is filtered, whereby 52 g. of a blackish brown dyestuff powder are isolated that dissolves in acidified water having a pH value <6 with a blue color.

By evaporating the filtrate in the vacuum, 72 g. of a pasty residue are obtained that dissolves in water with a blue color.

The solid and the pasty reaction product yield, when applied onto cellulosic materials, blue dyeings having good fastness properties.

EXAMPLE 45

20 g. of a green sulfur dyestuff prepared according to 45 the description given in Example 1 of U.S. Pat. No. 2,395,117 are suspended in 230 c.c. dimethylforma-

5 mide and heated to 80°. After the addition of 14 g. Na₂S (60 percent flakes), a deep blue dyestuff solution is formed. The temperature is then raised to 90° where it is kept for 30 minutes. 0.2 c.c. epichlorhydrin and 25 c.c. ethylenimine are then added to the solution which has cooled down to 60°. Subsequently, CO₂ gas is introduced into the reaction mixture, whereby the temperature reaches 80° within 15 minutes.

10 After the decay of the exothermic reaction, stirring is continued for another hour at a bath temperature of 100°. The reaction product, a slightly viscous, green solution can be indefinitely diluted with acidified water having a pH value <6.

15 When applied without the addition of reducing agents onto cellulose fibers, this solution yields clear green dyeings having good fastness properties.

Analogous results are obtained by performing the reaction in mixtures consisting of water and dimethylformamide.

20 What is claimed is:

1. A water-soluble sulfur dyestuff capable of dyeing textile materials in the absence of a reducing agent, said dyestuff being the product of reaction of a water-insoluble sulfur dyestuff, a reduction product thereof or a thiosulfuric acid derivative thereof at a temperature of from 15° to 120° C. with a member selected from the group consisting of ethylenimine, 1,2-propylenimine, N-acetylenimine, β -ethyleniminopropionamide, N-methylethylenimine, 2,2-dimethylethylenimine, 2,3-dimethylethylenimine, methyl- β -ethyleniminepropionate and 2-ethylethylenimine until a water-soluble dyestuff is obtained.

2. The water-soluble sulfur dyestuff of claim 1 35 wherein said reaction is carried out at a temperature of from 40° to 120° C.

3. The water-soluble sulfur dyestuff of claim 1 wherein, during said reaction, the pH is lowered to about 4 to 5.

4. The water-soluble sulfur dyestuff of claim 1 40 wherein said reaction is carried out in the presence of CO₂ or SO₂.

5. The water-soluble sulfur dyestuff of claim 1 wherein said reaction producing the same is carried out in the presence of a catalytic amount of ethylenechloride or epichlorhydrin.
